CLAIM

The ornamental design for a subscriber identification module card connector having battery base, as shown.

DESCRIPTION

FIG. 1 is a front, top and left side perspective view of a subscriber identification module card connector having battery base showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is another front, top and left side perspective view thereof while the battery base is pulled out.
